ROTATABLE CAR AND TRAIN-LINE COUPLER ARRANGEMENT

Frank H. Kayler, Alliance, Ohio, assignor to
American Steel Foundries, Chicago, Ill., a corporation of New Jersey

Application November 3, 1947, Serial No. 783,692

10 Claims. (Cl. 213—76)

This invention relates to car couplers for dumping cars and more particularly to an arrangement wherein the couplers are provided with means for connecting the air lines of the associated cars at substantially the same instant that the couplers are engaged and wherein the couplers are arranged to permit rotation of connected cars for dumping without disconnecting the same or the air lines.

In mines where the cars are travelled over long grades, it has been found that, as a condition of safety, it is desirable to equip these cars with automatic air brakes which, in general, follow the operating principles of those in use on standard railway equipment. Special problems, however, have arisen in connecting the air lines from one car to another inasmuch as modern mine cars are unloaded by being rotated 360° in a rotary dumper, while remaining coupled to other cars of a train. This fact makes it impossible to connect air lines by means of the conventional hose and interlocking connection of standard railway cars unless these connections are separated manually prior to rotating the cars and connected again after rotating, which not only involves considerable danger to the workman but is also time consuming.

The principal object of the invention is to provide an air line connection between such cars, as described, which need not be parted to permit dumping of the cars.

Another object of the invention is to provide means on mating car couplers for connecting the air conduits of associated cars at substantially the same instant that the couplers are coupled.

A further object is the provision of air transmitting conduits on mating couplers with a connection therebetween which will automatically connect on coupling and disconnect on uncoupling the couplers.

A still further object of the invention is to provide an air conduit on one coupler which is movable longitudinally thereof and urged toward the forward end thereof by spring means for tight engagement with the coaxial conduit formed on the mating coupler.

Another object of the invention is to devise a coupler wherein the head and shank have a swivel connection and wherein the air conduit is formed as part of the connection.

Another object is to devise a novel swivel connection between the coupler head and shank wherein means are provided to frictionally control rotation of said head with respect to said shank.

These and other objects of the invention will be apparent from the specification and the drawings, wherein:

Figure 1 is a fragmentary side elevation of connected cars and mating couplers with portions of the structure shown in longitudinal vertical section;

Figures 2 and 3 are views of one of the mating couplers shown in Figure 1, Figure 2 being a top plan view thereof, and Figure 3 being a front end view thereof;

Figures 4—6 are views of the other mating coupler shown in Figure 1, Figure 4 being a top plan view thereof, Figure 5 being a front end view thereof, and Figure 6 being a sectional view taken substantially in the plane indicated by line 6—6 of Figure 4;

Figures 7 and 8 are fragmentary longitudinal vertical sectional views of the mating couplers shown in Figure 1, Figure 7 showing the couplers in coupled position, and Figure 8 showing the couplers in uncoupled position; and

Figures 9 and 10 illustrate a modification of the invention, Figure 9 being a transverse sectional view similar to Figure 6 taken substantially on line 9—9 of Figure 10, and Figure 10 being a longitudinal vertical sectional view of the structure shown in Figure 9, the view being taken substantially in the plane indicated by line 10—10 of Figure 9.

Describing the invention in detail and referring first to the modification shown in Figures 1 to 8 inclusive, Figure 1 illustrates the ends of the two mine cars 2 and 4 connected to each other by means of mating couplers 6 and 8 which are of well known "tightlock" type.

The coupler 6, as best shown in Figures 2 and 3, comprises a hollow head 10 with an integral shank 12 extending from the rear thereof, the shank having a bifurcated extremity with spaced arms 14, 14 (Figure 1) on the adjacent sides of which are formed opposed converging V-shaped surfaces 16, 16 between which is received a flat end 18 of a tail bolt 20, said surfaces permitting relative vertical angling between the car 2 and coupler 6. The bolt 20 is loosely connected at said end 18 to the arms 14, 14 by a pin 24 whereby the coupler 6 is permitted horizontally angling with respect to car 2. The bolt 20 extends through a front draft gear follower 22 and connects with an associated draft gear (not shown) in the usual manner; said draft gear and follower being disposed in a center sill 26 of car 2, as will be readily understood by those skilled in the art.

The coupler head 10 comprises top and bottom walls 28 and 30 (Figure 3) and spaced vertical side walls 32 and 34 defining a pocket 36 for reception of a tongue or nose 38 (Figure 4) of the mating coupler 8. The head 10 is provided with a tongue or nose 40 integrally formed with walls 28, 30, and 32 of said head 10 and extending forwardly thereof. The tongue 40 is adapted to fit into a pocket 42 (Figure 4) in the head 44 of coupler 8.

The tongues 38 and 40 on the respective heads carry conventional locking means for interlocking engagement with each other upon coupling. The locking means carried by the tongue 40 is operatively connected to an operating mechanism, generally designated 45 (Figures 1 and 2), to lock and release the same with respect to the locking means in head 44 of the coupler 8. Further description of the locking and operating mechanism of these couplers will be omitted as they are of well known standard design and form no part of the present invention.

A cylindrical housing 46 is formed centrally on the top wall 28 of the coupler head 10 and extends from the forward edge of said wall 28 or 25 coupling face of the coupler 6 in a direction rearwardly of the head.

A hollow tubelike plunger 48 is slidably fitted within the housing and at one end projects through an inturned flange 50 (Figures 2, 7 and 8) on the rear extremity of the housing. This end of the plunger is connected to a pipe fitting or elbow 52 which in turn is connected to a flexible air hose 54 (Figures 1 and 3) supported from the car 2, the air hose being connected to the usual air brake piping of car 2. The other end of the plunger is formed with an enlarged collar 56 (Figures 7 and 8) which reciprocates with the plunger within the housing 46 and within which is press fitted a metallic sleeve 58 carrying a deformable cylindrical resilient gasket 60, such as rubber. The gasket 60 is so mounted within the sleeve 58 that it projects outwardly of the adjacent end of the collar 56 of the plunger.

The plunger is constantly urged outwardly of the forward end of the housing by a spring 62 sleeved over the plunger and compressed between the collar 56 on the plunger and the flange 50 of the housing. Outward movement of the plunger when the coupler 6 is uncoupled from its mating coupler 8 is limited by abutment of the fitting 52 against the flange 50 as at 64 (Figure 8).

The head 44 of the coupler 8 is provided, as hereinbefore noted, with a pocket 42 for receiving the tongue 40 of coupler 6. The pocket 42 is defined by top and bottom walls 66 and 68 and spaced side walls 70 and 72 forming the coupler head 44 (Figures 4 and 5). The walls 66, 68, and 70 are integral with the tongue 38 which, as hereinbefore mentioned, is adapted to fit into pocket 36 in head 10 of coupler 6. The side walls 70 and 72 converge toward the rear of said head 44 and with the top and bottom walls 66 and 68, which also converge at their rear extremities, merge at the rear of the head into a centrally disposed substantially cylindrical portion 74, the axis of which coincides with the longitudinal center line of coupler 8.

The portion 74 has a swivel connection with a shank 76 which at its extremity remote from the head 44 is provided with spaced arms 78, 78 defining a slot 80 therebetween within which is received a flat end of a tail bolt 82, the bolt 82 being operatively connected to a draft gear mechanism (not shown) through a follower 84 positioned in 75

a center sill 86 of car 4. The adjacent sides of the arms 78, 78 are formed with opposed converging V-shaped surfaces to accommodate vertical angling of the bolt 82 which has the before-mentioned flat end thereof loosely connected to the arms 78, 78 by a pin 88, whereby relative vertical and horizontal angling between the car 4 and coupler 8 is accommodated.

The swivel connection between the portion 74 and the shank 76 is located at approximately the same longitudinal axis as the connections between the couplers and the cars and comprises a circumferential annular flange 90 on the portion 74 and a similar annular flange 92 on the abutting end of the shank 76. The flanges 90 and 92 are received within a split clamp band or ring, generally designated 93, comprising two mated parts 94 and 96. The part 94 comprises a semi-cylindrical web 98 at one end of which are formed a pair of axially spaced lugs 100, 100 (Figure 4) and at the other end of web 98 is provided a radially outturned lug 102. At the opposite side of the web 98 are formed radially inwardly extending flanges 104, 104. The part 96 is generally similar to the part 94 and comprises a semi-cylindrical web 106 having a lug 108 at one end fitting between the spaced lugs 100, 100 and pivoted thereto by a pin 110. At its opposite end the web 106 has a radially outturned lug 112 (Figure 6). A bolt 114 extends through aligned openings in lugs 112 and 102 (Figure 6). A spring 116 is sleeved over the bolt 114 and is compressed between the lug 112 and a nut 118 threaded on the lower end of said bolt. The spring urges a head 120 of the bolt 114 against the lug 102 thus drawing the parts 94 and 96 together by pivoting the same on the pin 110, and producing hoop tension in the webs 98 and 106 of the respective parts which overlie the flanges 90 and 92. The web 106 is also provided at opposite sides thereof with radially inwardly extending flanges 122, 122 (Figure 7). The flanges 104, 104, and 122, 122 receive the circumferential flanges 90 and 92 on the portion 74 of the head and shank 76 therebetween and hold them together holding the head 44 and shank 76 from separation.

The shank 76 and head 44 of the coupler 8 are restrained against relative free rotation by means of a split friction band or lining 124 (Figures 6 and 7) surrounding and in frictional engagement with the outer peripheries of the flanges 90 and 92. The friction lining may be of any suitable material such as standard brake lining and may be secured, as by vulcanizing, to a flexible liner 126, such as rubber. Preferably the liner 126 overlies the friction lining without being secured thereto, said liner serving as a backing for the friction lining and being seated against the inner surfaces of the webs 98 and 106 between the flanges 104, 104 and 122, 122 of the parts 94 and 96 of the clamp band. Preferably the lining 126 is not anchored to said webs 98 and 106 although it may be so secured, if desired. It will be noted that the spring 116 produces hoop tension in the clamp band which draws the friction lining tightly against the outer peripheries of the flanges 90 and 92, and compresses the liner 126 which assists in seating the friction lining complementally against these peripheries whereby friction is developed between the flanges 90 and 92 and the friction lining 124, and free rotation of the head 44 relative to the shank 76 is prevented. Of course, the liner 126 may be eliminated and the friction lining 124 may be divided into several segments and fixed, as by rivets, di-

rectly to the respective webs 98 and 106. In either event, the lining 124 is disposed between the flanges 104, 104 and 122, 122 respectively.

An axial opening or channel or passage 128 forming part of an air conduit is provided in the portion 74 of the head 44, the passage 128 extending through the length of a boss or protuberance 130 formed centrally on the top wall 66 of the head 44, the boss extending from the rear of the head 44 to the forward edge or coupling face of said top wall 66 in alignment with the housing 46 on the head 10.

A sleeve 132, carrying a cylindrical resilient gasket 134, such as rubber, is press fitted into the forward extremity of the opening 128 in the boss 130. The gasket 134 extends beyond the coupling face of the coupler 8, that is, beyond the forward edge of the top wall 66 and in substantially axial alignment with the plunger 48 so that when the couplers 6 and 8 are coupled, the gaskets 60 and 134 are pressed against each other by action of the spring 62 reacting against the plunger whereby an airtight connection is provided between the passage 128 and the passage in the hollow plunger 48.

The opening 128, at its rear extremity, extends through an axially projecting centrally disposed annular flange 136 (Figure 7) on the portion 74 of the head 44. The flange 136 fits into a complementary annular opening 138 in the adjacent end of the shank 76.

A sleeve 140 is press fitted into flange 136 but projects outwardly therefrom and into opening 138. The sleeve 140 may for all practical purposes be regarded as part of the shank 47. A sleeve 143 is press fitted into the opening 138 and carries a resilient gasket 145, such as rubber, said sleeve 143 snugly embracing an end 144 of said gasket, said end 144 being seated against the rear of opening 138 which is of reduced diameter. The other end, indicated 142, of the gasket 145 extends into the sleeve 140. Preferably, the end 142 of gasket 145 fits snugly into the sleeve 140; however, if desired, it may be formed to fit into sleeve 140 under initial compression, that is, forced tightly into sleeve 140.

A passage or opening 146 (Figure 7) extending from the bottom of the shank 76 communicates with the passage 128 through the opening in gasket 145, as may well be seen in Figure 7. The passage 146 is connected through a fitting 148 to a flexible rubber hose 150 which in turn is connected to the standard air piping (not shown) of car 4.

In operation as the couplers are coupled, the lines 54 and 150 will simultaneously connect, that is, gasket 60 will be brought to bear against gasket 134. It will be noted that gaskets 60 and 134 are provided with generous bearing areas so that a slight misalignment therebetween will not affect their function. The gaskets 60 and 134 are held in tight abutment with each other by the compression spring 62 urging plunger 48 outwardly of housing 46. As air is transmitted through the lines 54 and 150 and passages 146, 128 and the passage or opening through the plunger, the outward pressure of the air expands the rubber gasket 145 and presses the outer surface of end 142 thereof against the inner surface of collar 140 and the end 144 of gasket 145, which distorts under pressure, is pressed tightly against the rear of opening 138. This action of the air pressure on gasket 145 seals the connection between passages 146 and 128, which at their adjoining ends are disposed at the axis of rotation

between the head 44 and shank 76. It is intended that the air pressure will not be on during dumping of cars so that abrasion of gasket 145 during rotation of the connection between coupler head 44 and shank 76 is prevented.

Referring now to the embodiment shown in Figures 9 and 10, wherein the parts similar to those shown in the previous embodiment are designated by the same reference characters, the 10 coupler 8 comprises a coupler head 44 having a swivel connection with the shank 76. The connection comprises a portion 74 on the rear of the head 44 with an annular circumferential flange 90 and a similar abutting flange 92 on the 15 adjacent end of the shank 76. The flanges 90 and 92 are received within a split clamp ring or band 93 comprising mated parts 94 and 96. Part 94 differs from that shown in the previous modification in that the intermediate portion of the 20 web 98 forms a housing 200 with portions of the inwardly extending flanges 104, 104. One end of the web 98 is formed with spaced lugs 100 and the other end with an outturned lug 102.

Part 96 comprises a semi-cylindrical web 106 25 having a lug 108 at one end connected by a pin 110 to lugs 100. Web 106 has an outturned lug 112 at its opposite end connected to a lug 102 by a bolt and nut assembly 114.

Flanges 122, 122 at opposite sides of the web 30 106 and flanges 104, 104 on the web 98 receive the flanges 90 and 92 of the head and shank therebetween and hold them together compressing gaskets 242 and 244 against each other as at 245, gasket 242 being mounted in the rear extremity 35 of opening 128 and gasket 244 being mounted in the adjacent opening 138 in shank 76.

Within the housing 200 at one side of the axis of the connection between the shank and portion 74 are pivoted a pair of latches 204 and 206 by means 40 of a pin 208 extending through flanges 104, 104 and corresponding ends of said latches.

The latch 204 overlies flange 90 and the latch 206 overlies flange 92, said latches having heads 210 and 212 respectively releasably engageable in 45 complementary notches or recesses 214 and 216 respectively, in the peripheries of the associated flanges 90 and 92.

The recesses 214 and 216 and the respective heads 210 and 212 are provided with tapered faces 50 as at 218, 218 and 220, 220 respectively, to provide a cam action for raising the respective latches upon rotation of the head 44 or shank 76 respectively, during a car dumping operation. It will be noted that the rotation of the head or shank is limited to a counterclockwise direction, as shown by the arrow in Figure 9, by the latches 204 and 206. The latches 204 and 206 are urged 55 against the flanges 90 and 92 by springs 224, 224, diagrammatically illustrated in Figure 10, each spring being compressed between its associated latch adjacent the head thereof and the housing 200 and being held in position by a lug 226 on the associated latch.

In operation, if the car to which the shank 76 60 is connected is dumped, the latch 206 will pivot upwardly by sliding on faces 218 and 220 on the head 212 thereof and associated notch 216 respectively, permitting the shank 76 to rotate relative to the band 93, the band being held in position by the latch 204 having its head 210 engaging in the recess 214.

If the head 44 is rotated relative to the shank 76, the latch 204 will pivot upwardly by sliding on faces 218 and 220 on the head 210 thereof and 65 associated notch 214 respectively, the band being

held against rotation by the head 212 on the latch 206 engaging in the recess 216 in the flange 92. This arrangement not only holds the band in a fixed position but also equalizes the wear on the flanges 104 and 122 of the parts 94 and 96 of the band. It will be understood that normally the latches restrain the head 44 from rotating with respect to the shank 76 when uncoupled from its mating coupler whereby it is held in position ready for coupling.

The duct 146 in the present instance extends upwardly through the shank and connects with the duct or passage 128 through the cylindrical gaskets 244 and 242 and at its upper end connects to a flexible air hose 150 of the car 4 through a pipe fitting 148.

It will be appreciated that I have provided a novel connection between the air-lines 54 and 150 of connected cars 2 and 4 which will part automatically when the cars are uncoupled and will connect the lines when the cars are coupled.

There is no necessity for disconnecting the air lines when either car is dumped and when the cars are uncoupled, the swivel head 44 will be held in position for coupling.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. In a car coupler, the combination of a head portion to couple to a companion head, a draw bar portion adapted for connection to an associated car, said portions being rotatable relative to each other, and means for connecting said portions and holding the same against disassembly comprising abutting radially extending members on said portions, a clamp ring surrounding and embracing said members, and means for releasably holding said members against rotation relative to each other comprising a latch adjacent the periphery of each member having one end pivoted to said clamp ring and having a portion at its other end receivable within a complementary notch in the associated member, and spring means compressed between said ring and each latch intermediate the ends thereof for rotating the respective latches on their pivots and urging said portions thereof toward said flanges and into said notches therein.

2. A coupler having a head, a shank, circular flanges on said shank and head, said flanges having relatively large vertical plane areas abutting each other, locking means engaging said flanges to hold said head and shank against longitudinal movement relative to each other but accommodating relative rotative movement therebetween, and friction means engaging both flanges to resist said rotative movement whereby said head is held in normal operative position to couple with a companion head, said friction means comprising a band of friction material carried by the locking means and embracing the peripheries of said flanges for resisting said movement until sufficient rotational force is applied against said head and shank to overcome the resistance of said friction means as when one car is rotated relative to the connected car.

3. In a railway car coupler, a head and shank, a rotatable connection therebetween, a fluid conducting passage extending through said head and shank and said rotatable connection, and

a connection between the adjacent ends of the portion of said passage in said head and the portion of said passage in said shank comprising a cylindrical flexible member mounted at one end thereof in one of said passage ends and projecting at its other end into the other of said passage ends, said member being distortable and expandable under fluid pressure for tightly engaging at its outer surface the inner surfaces of said passages for sealing the connection therebetween.

4. In a car coupler, the combination of a head to couple to a companion head, a draw bar to connect to an associated car body, a rotatable connection therebetween comprising annular portions on said head and draw bar, said portions having relatively large vertical plane areas abutting each other, a member surrounding and receiving said portions therein for holding said draw bar and head in assembled relation, a friction element between said member and said portions in frictional engagement with the latter for preventing free relative rotation between said draw bar and head, and resilient means stressed and confined between said member and said element.

5. In an automatic coupler, a head, a shank, and a swivel connection therebetween, said connection comprising annular flanges on said head and shank, said flanges having relatively large vertical plane areas abutting each other, a clamp band receiving said flanges therein for holding said head and shank in assembled relation, a friction lining in said band in frictional engagement with said flanges, and means operatively associated with said band for producing hoop tension thereon for urging said lining against said flanges and thereby preventing free relative rotation between said head and shank.

6. A railway car coupler comprising a head and a shank, a rotatable connection between the head and shank accommodating relative rotation therebetween on the longitudinal center axis of said coupler and comprising a clamp member surrounding said head and shank and interlocked therewith, means in engagement with said head and shank for resisting relative rotation therebetween, and resilient means oriented to deliver a force transaxially of said axis and reacting between said member and said first-named means for urging the latter against said head and shank.

7. A railway car coupler comprising a head and a shank, a rotatable connection between the head and shank accommodating rotational movement therebetween on the central longitudinal axis of said coupler, said connection including circular flanges on the head and shank, said flanges having vertical plane surfaces abutting each other, said connection including a clamp surrounding the flanges and adjacent ends of said head and shank and interlocked therewith, means carried by said clamp for engagement with said flanges for resisting rotational movement therebetween, a fluid passage in said head and shank extending through said connection coaxially with said axis and adapted for connection with associated fluid-conducting means, and a fluid-tight connection between the portion of said passage in said head and the portion thereof in said shank comprising abutting distortable elements in the adjacent ends of said portions pressed and held against each other through the action of said clamp in connecting said head and shank, said elements having aligned openings communicating with said portions and slidably abutting each

other along vertical plane faces extending transaxially of said axis.

8. In an automatic railway car coupler, a head and a shank arranged end to end in abutting relationship along rigid complementary bearing areas, a coupling between said head and shank accommodating rotation therebetween on an axis extending longitudinally of the coupler, a fluid conduit in said head and shank extending along said axis of rotation through said areas, and a fluid-tight flexible rotatable connection at said areas between adjacent ends of the portions of said conduit in said head and shank accommodating rotation between said portions.

9. A railway car coupler comprising a head member and a shank member, a rotatable connection between said members accommodating rotation therebetween on an axis extending substantially longitudinally of the coupler, a fluid passage comprising a portion in each member and extending at adjacent ends coaxially with said axis through said connection, and means affording a fluid-tight flexible rotatable connection between said portions comprising resilient gaskets fitted within the ends of said portions and in abutment with each other along plane faces extending transaxially of said axis, said gaskets being completely surrounded by said members and being distortable upon admission of fluid into said passage for compression by said fluid against said members for distorting said gaskets for tightly engaging the same with each other along said abutting faces and with said members.

10. A coupler comprising a head and shank, a rotatable connection therebetween accommodat-

ing their relative rotation on an axis extending longitudinally of the coupler, and a fluid passage comprising a portion in the head and a portion in the shank arranged end to end and extending substantially through the center of said connection between said head and shank, resilient bushings in the adjacent ends of said passages connected to said head and shank and in abutment with each other along faces extending transaxially of said axis for slidable movement along said faces during relative rotation between said head and shank, said bushings being distortable by the pressure of fluid admitted into said passage for tight abutment with each other and with said head and shank, respectively, whereby said bushings provide a sealed connection between said passages.

FRANK H. KAYLER.
